The ornamental design for a foam roller, as shown and described.

DESCRIPTION

FIG. 1 is a top, front, right perspective view of the foam roller;

FIG. 2 is a front elevational view thereof;

FIG. 3 is a back elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines shown in the drawings are for the purpose of illustrating portions of the foam roller, which form no part of the claimed design.

The foam roller is shown with portions cut away (indicated by break lines and brackets) to indicate a non-specified length. The appearance of any portion of the foam roller between the break lines forms no part of the claimed design.
